UNITED STATES PATENT OFFICE.

LEONARD W. DOAK, OF DRAVOSBURG, PENNSYLVANIA.

SUSPENSION APPARATUS FOR STEAMBOAT RUDDERS.

Application filed April 12, 1926. Serial No. 101,388.

My invention relates to a suspension apparatus and while primarily intended for steamboat rudders' suspension, it will be obvious that the device may be employed for 5 any other purposes wherein it is found to be applicable.

Important objects of the invention are to provide a device of the character stated, in a manner as hereinafter referred to, which 10 is simple in its construction and arrangement, strong, durable and efficient in its use, easily operable, and comparatively inexpensive to manufacture and install.

With the foregoing and other objects in 15 view which will appear as the description proceeds, the invention resides in the combination and arrangement of parts and in the details of construction hereinafter described and claimed, it being understood 20 that changes in the precise embodiment of the invention hereinafter disclosed can be made within the scope of what is claimed without departing from the spirit of the invention.

25 In the drawing wherein like numerals of reference designate corresponding parts throughout the several views:—

Figure 1 is a side elevational view partly 30 in section, of a suspension apparatus constructed in accordance with the invention.

Figure 2 is a rear view of the housing and associated parts, the latter being partly 35 in section.

Fig. 3 is an elevation partly in section of 40 the intermediate link.

Referring in detail to the drawing, 1 denotes a vertically disposed cylindrical bearing housing provided with a bore 2. The housing 1 is adapted to be fixedly secured in 45 position and for that purpose is integrally formed with a plurality of apertured securing brackets 3, preferably disposed on the rear side of the housing 1. It will, of course, be obvious that the housing 1 may be fixed in position in any other suitable manner to best meet conditions found in practice. The housing 1 is formed with an enlarged upper end 4 having a corresponding 50 enlarged bore 5 for the purpose to be described.

A tubular stem 6 is rotatably mounted in the bore 2 of the cylindrical housing 1. The stem 6 is provided with a collar 7 disposed adjacent to the upper end thereof, and with 55 an elongated collar 8 disposed adjacent to the lower end of the stem 1. The collars 7

and 8 are preferably integrally formed with the stem 6 and are provided to reduce friction to facilitate the rotation of the latter in the bearing housing 1.

The lower end of the stem 6 is formed to provide a flattened socket 9 suitable for attachment to the stock of a steamboat rudder or to any other structure adaptable to my improved device. The stem 6 is further 60 formed with an annular flange 10, which abuts against the lower end of the housing 1 and is disposed directly against the lower end of the elongated collar 8. The flange 65 10 is intended to prevent as nearly as possible, the entrance of water into the housing bore 2 when the device is utilized for steamboat rudder suspension. Although the lower end of the housing 1 is normally not immersed in the water, it is in proximity 70 thereto and is subjected to continuous 75 splashing from the operation of the propeller wheel.

The stem 6 is suspended in the housing 1 by a series of interconnected suspension 80 links, namely, the stem link 11, the intermediate link 12, and the hanger link 13. The stem link 11, is connected in the bore 14, of the stem 6, by means of a bolt 15. The latter extends transversely through the stem 85 6, adjacent to the upper end thereof, and through the aligned apertured bosses 16, which are formed integral with the stem 6, and disposed in the stem bore 14 on respective sides of the link 11. The upper end of the stem link 11 is provided with an integrally formed depending pivoting pin 17 90 which engages the pivoting socket 18 formed integrally with the lower end of the intermediate link 12. The latter is also provided 95 at its upper end with a depending integrally formed pivoting pin 19.

A hanger 20 is adjustably fixed in the supporting structure 21. The hanger link 13 is secured to the hanger 20 by means of a 100 bolt 22. The lower end of the hanger link 13 is provided with an integrally formed pivoting socket 23 engaged by the pivoting pin 19 of the intermediate link 12.

The stem 6 is vertically adjusted in the 105 housing 1 by the adjustment of the hanger 20 in the supporting structure 21. The upward adjustment of the stem 6, is of course limited by the abutment of the flange 10 against the lower end of the housing 1.

110 A forward extending operating lever 24, is fixedly clamped to the upper end of the

stem 6 by means of a bolt 25. The lever 24 is further fixed in position by a pair of tie rods 26, the forward ends of which are secured in the lever 24, as indicated at 27, 5 while the rear ends thereof are attached against the respective sides of the stem 6 by the bolt 15.

A comparatively heavy collar 28 is loosely mounted on the stem 6 and is positioned in 10 the enlarged bore 5, of the enlarged upper end of the housing 1. The collar 28 is provided to carry the stem 6 when the former is engaged by the rear ends of the tie rods 26 in the event of accidental breakage of any of 15 the suspension links 11, 12 and 13. The stem 6 while carried by the collar 28, as above stated, is operable for temporary use until repair to the suspension links are made.

The enlarged housing bore 5, and the suspension link pivoting sockets 18 and 23 are 20 adapted to be packed with lubrication to facilitate the operation of the device. A tube 28 communicates with the housing bore 2 and is intended to permit of supplying lubrication to the elongated stem collar 8 and 25 the contacting lower end of the housing 1.

The construction of the device permits of 30 the rotation of the stem 6 in the housing in either direction to a distance permitted by the interconnected links 11, 12 and 13, but such partial rotation is sufficient for the 35 operation of a steamboat rudder for which the mechanism is primarily intended.

What I claim is:

35 1. A suspension apparatus comprising a bearing housing adapted to be fixedly secured in the vertical position, a stem rotatably mounted in said housing, a hanger member adapted to be fixed in position in a supporting structure, and a series of interconnected links connected with said hanger member and with said stem for shiftably suspending the latter in said housing, and 40 an operating lever fixed to said stem for shifting the latter in said housing.

45 2. A suspension apparatus for steamboat rudder comprising a cylindrical bearing housing adapted to be fixedly secured in the

vertical position, a stem rotatably mounted in said housing, the lower end of said stem 50 formed to permit of its attachment to the rudder, a hanger member adapted to be fixed in a supporting structure, and a series of interconnected links connected with said hanger member and with said stem for shiftably suspending the latter in said housing, and an operating lever fixed to said stem for shifting the latter in said housing.

3. In combination, a suspension apparatus for a steamboat rudder comprising a cylindrical housing having an enlarged upper end and adapted to be fixedly secured in the vertical position, a stem provided with a pair of integrally formed collars mounted in said housing, said stem formed with a flange 65 abutting against the lower end of said housing, the lower end of said stem formed to permit of its attachment to the rudder, a hanger member adapted to be connected to a supporting structure, a hanger link having 70 its upper end connected to said hanger member and formed with a pivoting socket at its lower end, a stem link provided with a pivoting pin at its upper end, a bolt extending transversely through the upper end of said 75 stem and securing said stem link to said stem, an intermediate link provided at its upper end with a depending pivoting pin seated in the pivoting socket of the hanger link, the lower end of said intermediate link 80 provided with a pivoting socket, the depending pivoting pin of said stem link engaging in the pivoting socket of the said intermediate link, means for adjusting said hanger member in its supporting structure for vertically adjusting said 85 stem in said housing, a collar loosely mounted on said stem and positioned in said enlarged end of said housing, an operating lever fixed to the upper end of said stem, and 90 a pair of tie rods connected at one end to said lever and at the other ends to said stem by said bolt, substantially as described and for the purpose set forth.

In testimony whereof I affix my signature.
LEONARD W. DOAK.
